Fenelon B. Brock

UNITED STATES PATENT OFFICE.

MARY STARMER, OF NEWPORT NEWS, VIRGINIA.

GARMENT-SUPPORTER.

1,375,118.

Specification of Letters Patent. Patented Apr. 19, 1921.

Application filed November 22, 1919. Serial No. 339,816.

To all whom it may concern:

Be it known that I, MARY STARMER, a citizen of the United States of America, residing at Newport News, in the county of Warwick and State of Virginia, have invented 5 new and useful Improvements in Garment-Supporters, of which the following is a specification.

The invention relates to garment supporters designed particularly for use as one-point-suspension devices supported from the waist line, which in the form for adults is from the corset, and from a waist belt when worn by juniors.

15 The primary object of the invention is a garment or stocking supporter composed of relatively few parts thus rendering it simple in construction and in its adaptability for use, comparatively inexpensive in cost 20 of manufacture, and efficient and facile in its adjustment and in performing the required functions of a device of this character.

In the accompanying drawings I have 25 illustrated two complete examples of the physical embodiment of the invention, one form for juniors and the other form for women's hose supporters, the parts being combined and arranged according to the 30 best modes I have thus far devised for the practical application of the principles of the invention, but it will be apparent that the subject matter of the invention may be embodied for use by men, and the adjusting 35 buckle, for instance may be incorporated as an integral part of men's suspenders.

Figure 1 is a front view of the hose supporter as adapted for junior wear adapted to be supported from a waist belt and pinned, 40 by the forked elastics, to the hose.

Fig. 2 is a vertical, sectional view, with parts exaggerated for convenience of illustration, of the device of Fig. 1.

Fig. 3 is a rear or back view of the adjuster or pin-buckle.

Fig. 4 is a view showing the invention embodied as a woman's hose supporter, a fancy finish being attained by utilizing a tassel for adjusting the length of the supporters.

Fig. 5 is a sectional detail of Fig. 4.

For purposes of description the junior supporter will first be referred to, which consists of the wide elastic webbing 1 of 55 suitable length, provided at its upper end with the fastening pin 2 carried by the stay

or plate 3, preferably of metal, and to which the pin 2 is fixed at one end and may be hooked or caught at the other end. The pin 2 is the subject matter of a co-pending 60 application for patent filed by me, and forms no essentially patentable part of the present invention.

No stitches are employed in securing the stay plate 3 to the web or elastic 1, but instead I prefer to clamp the web to the plate, 65 as shown in Fig. 2, where the web is threaded through the guide slot 4 in front of the rear integral guide bar 5, and then by a reverse bend 6 at the top of the stay plate the 70 upper end of the elastic webbing is firmly and securely clamped to the plate. When attaching the supporter to the waist belt, the pin 2 is slipped through the belt in usual manner and the material of the belt is held 75 between the pin 2 and the elastic at the rear of its locked or clamped joint.

The lower end of the web 1 is attached in similar manner to the adjusting buckle 7, but in addition to the webbing 1, the forked 80 tapes 8 and 9 are also clamped to the buckle, and for this purpose, the forked attaching tapes, which are in actual practice a single piece folded upon itself to form the two 85 tapes 8 and 9, are folded and clamped, at the bend in the tape, in between the folds of the reverse bend 10 formed at the back and bottom of the buckle 7. The front of the buckle presents a smooth surface that may be ornamented as desired, as may also the 90 plate 3 at the top of the supporter, and the reverse bend 10 is clamped by suitable dies to securely hold the web and forked tape against dislodgment.

The fold in the tape, it will be understood, 95 is on the bias, and the lower ends of the forks of the tape are also cut on the bias, so that the attaching devices 11 and 12 (each of which includes a pin 13 for insertion into the hose) are alined parallel with the buckle 100 7, and these attaching devices 11 and 12 are clamped at 14 to the forked tapes in manner similar to the attachment of the stay plate 1 and buckle 7 to the wide web 1.

The buckle 7 is adjustably attached to the 105 web 1 above the fixed joint at 10, by means of the inverted U-shape pin 15, which has its prongs extending down through the openings 16 16 in the top of the buckle, and each prong is provided with an inwardly bent lug 110 17 which guides its movement back of the guide plate 18 of the buckle. This guide

plate, is integral with the front plate of the buckle and is bent down behind it to form a space for the accommodation of the U-shape pin, and back of the pin-guiding plate a second plate 19 is provided, preferably integral with the plate 18 and buckle 7, so that the web may be threaded and guided between these two plates, as best seen in Fig. 2.

In Figs. 1 and 2 the web 1 is extended its full length and the pin is in fastened position. Now in order to adjust the supporter and shorten the length of the working part of the device, the U-shape pin is grasped by the hand hold 20, which is preferably a metal roll or plate clamped over the wire cross bar of the pin, and the pin withdrawn from the elastic, the plate 18 acting as a push-off for the web and allowing the points of the prongs to be withdrawn, while the lugs 17 and the upper or top wall of the guide-plate 18 prevent the bodily dislocation of the pin. With the pin points withdrawn, the buckle 7 may be slid up on the web, the slack falling down at point S in Fig. 2 back of the buckle and back of the upper end of the forked tapes 8 and 9, until the desired length of web is attained, after which the pin is pushed downwardly and its points inserted in the web as shown.

When employed as a support for women's hose the web 1^a is preferably sewed to the corset C, and a tassel 21 on the end of the cord 22, which is passed up between the plate 18 and the front face of the web and buckle 7^a and attached as at 23 to the web, is used to adjust the device. Thus the buckle 7 is grasped in one hand and a pull on the tassel draws the cord and web downwardly through the lower opening 7^b of the buckle 40 until the web 1^a is shortened as required, whereupon the pin 15^a is pushed into place with its points as in Fig. 2.

In Fig. 4 an attaching pin is indicated by

dotted lines at 24, to pin the buckle to the hose or to a pad on the hose as desired, and this pin may be secured to the guide plate 10 of the buckle in approved manner.

What I claim is—

1. The combination in a hose supporter with a web and end attaching means, of a buckle having a fixed guide plate and secured at the lower end of the web, and a U-shaped pin having guide devices slideable between the buckle and plate.

2. In a garment supporting device the combination with the web and a slideable buckle secured at its lower end, said buckle having a spaced guide plate, of a U-shaped pin slideable between said plate and buckle and adapted to engage the web, and means for limiting the movement of the pin.

3. In a garment supporting device, the combination with the web, of a buckle slideable on the web and secured at the lower end thereof, said buckle formed with a guide plate and an adjoining plate to guide the web, a U-shaped pin, slideable between the guide plate and buckle, and means on the pin to engage the guide plate to retain the pin against loss.

4. In a garment supporting device the combination with a web, of a buckle fixed at the end of the web and slideable thereon, said buckle having a spaced plate and formed with top openings, a U-shaped pin slideable in the openings of the buckle having lugs guided between said buckle and plate.

5. In a garment supporter the combination with a buckle having a pin guiding plate and a U-shaped pin having lugs between said buckle and plate, a back plate on the buckle and a web passed between said guide plate and back plate, and a reversely bent rear plate on the buckle to which the end of said web is clamped.

MARY STARMER.
